AUTOMOBILE LIFT

Cyrus J. Bristol, Des Moines, Iowa, assignor to
 Globe Hoist Company, Des Moines, Iowa, a
 corporation of Iowa

Application March 1, 1937, Serial No. 128,411

2 Claims. (Cl. 254—93)

My invention relates to that class of automobile lifts in which an upright cylinder is provided and a plunger therein is raised and lowered by fluid pressure. In hoists of this kind it is necessary to have a plunger bearing at the top of the cylinder, and also a second bearing spaced below the first to prevent lateral movement of the upper end of the plunger when elevated, and lifts of this class were usually provided with means for positively limiting the upward movement of the plunger, and such means were necessarily located in the space between the plunger and cylinder and, hence, were not readily accessible, and considerable time and effort were required to remove the plunger from the cylinder.

The object of my invention is to provide means of simple, durable and inexpensive construction for readily, quickly and easily removing or replacing the plunger and also positively limiting the upward movement of the plunger.

Referring to the accompanying drawing, Figure 1 shows a vertical central sectional view through a part of an automobile hoist mechanism embodying my invention.

Figure 2 shows a transverse sectional view on the line 2—2 of Figure 1.

Figure 3 shows a detail vertical central sectional view illustrating the lower portion of the plunger and cylinder, and illustrating the stop arms in their withdrawn position; and

Figure 4 shows a sectional view on the line 4—4 of Figure 1.

The reference numeral 10 indicates an upright cylinder of ordinary construction open at its upper end and closed at its lower end. At the upper end of the cylinder there is fixed a plunger bearing 11, and at a point spaced below the bearing 11 is a combined plunger bearing and stop member 12 firmly fixed in position on the cylinder by rivets or the like. This bearing member and stop is preferably formed with passageways 13 so that fluid may freely move up and down past it.

Slidably mounted within the cylinder is a cylindrical plunger 14 open at its top and having a plunger head 15 fixed in position spaced above its lower end, and in this lower end of the plunger which extends below the head is a series of openings 16, for purposes hereinafter made clear. A screw-threaded rod 17 is rotatably mounted in an upright position in the plunger head 15, and it is provided at its upper end with an enlarged head 18, and between the head 18 and the plunger head 15 is a washer 19. Mounted on the lower end of the screw-threaded rod 17 is a nut 20, and pivoted to this nut are four arms 21 extended

outwardly through the openings 16 in the plunger. The head 18 is provided with a transverse slot 22, or the like, adapting it to be engaged for turning by an ordinary wrench or like implement, and this may be done by inserting the 5 implement through the open top of the plunger.

In practical use the plunger bearing and stop member 12 is riveted or otherwise firmly fixed in position. When it is desired to insert the plunger the nut 20 is moved to the position shown 10 in Figure 3, so that the arms 21 are withdrawn, thereby permitting the plunger to be readily and easily inserted within the cylinder past both of the bearings therein. When this has been done the operator inserts a wrench or the like through 15 the open upper end of the plunger and engages the head 18 and rotates it until the nut 20 firmly engages the under surface of the plunger head 15, and when this is done a fluid-tight joint is provided at the point where the screw-threaded 20 rod passes through the plunger head. At the same time the arms 21 are caused to project outwardly beyond the plunger, and they are firmly held in this position. Obviously, when fluid pressure is applied within the cylinder the plunger 25 will be elevated, and when the arms 21 reach the stop device 12, the upward limit of the plunger will be stopped and the plunger will have two spaced apart bearings for firmly holding it 30 against lateral movement when in its maximum elevated position.

In practice I have found that a very substantial saving in the original cost of this part of the lift device may be effected by means of my improvement, and a very substantial saving 35 in both time and labor is effected when it is desired for any reason to remove and replace the plunger.

I claim as my invention:

1. In a hoist, the combination of an upright 40 cylinder open at its upper end, a plunger slidably mounted in the cylinder and open at its upper end and provided with a lower head spaced above the lower end of the cylinder, the projecting lower end of the plunger being formed with 45 guide openings, two plunger bearings fixed to the cylinder, one at its upper end portion and the other spaced below the first, a screw-threaded rod extended through and rotatably mounted in said piston head, having its upper end shaped to receive an implement for rotating the rod, a nut mounted on the rod below the piston head and arms pivoted to the nut and extended through the openings in the lower end of the plunger, said arms being so shaped that when the nut is at 50 55

its upper limit the outer ends of the arms will project beyond the plunger and co-operate with the lower bearing on the cylinder to limit the upward movement of the plunger, and when the nut is at its lower limit, the outer ends of said arms will be withdrawn to permit the removal of the plunger from the cylinder.

2. In a hoist, the combination of an upright cylinder open at its upper end, a plunger slidingly mounted in the cylinder and open at its upper end and provided with a lower head spaced above the lower end of the cylinder, the projecting lower end of the plunger being formed with guide openings, two plunger bearings fixed to the cylinder, one at its upper end portion and the other spaced below the first, a screw-threaded rod extended through and rotatably mounted in said piston head, having its upper end shaped to receive an implement for rotating the rod, a nut

mounted on the rod below the piston head and arms pivoted to the nut and extended through the openings in the lower end of the plunger, said arms being so shaped that when the nut is at its upper limit the outer ends of the arms will project beyond the plunger and co-operate with the lower bearing on the cylinder to limit the upward movement of the plunger, and when the nut is at its lower limit, the outer ends of said arms will be withdrawn to permit the removal of the plunger from the cylinder, said screw-threaded rod having a head at its upper end and a washer between said head and the upper surface of the piston head, and whereby when the screw-threaded rod is at its lower limit of movement fluid from the interior of the cylinder will be prevented from entering the plunger.

CYRUS J. BRISTOL.
